UNITED STATES PATENT OFFICE.

TONJES AUGUST CARL BOTH, OF NEW YORK, N. Y., ASSIGNOR, BY MESNE ASSIGNMENTS, TO THE ZEE SOCKET & MFG. CO., OF BOSTON, MASSACHUSETTS, A CORPORATION OF MASSACHUSETTS.

MECHANICAL MOVEMENT AND ELECTRIC-LIGHT SOCKET.

1,029,044.

Specification of Letters Patent. Patented June 11, 1912.

Original application filed December 30, 1911, Serial No. 668,632. Divided and this application filed March 20, 1912. Serial No. 694,989.

To all whom it may concern:

Be it known that I, TONJES AUGUST CARL BOTH, a citizen of the United States, and a resident of New York, in the county of New York and State of New York, have invented certain new and useful Improvements in Mechanical Movements and Electric-Light Sockets, (Case U,) of which the following is a specification, taken in connection with the accompanying drawings, which form a part of the same, this application being a division of my application for mechanical movement and electric-light socket, filed December 30, 1911, Serial No. 668,632.

My invention relates to mechanical movements adapted for universal application. Further to electric light sockets and to certain details of construction of both the mechanical movement and the electric light socket, which will be more fully hereinafter described in the specification and pointed out in the claims.

I have shown my mechanical movement as a switch mechanism in an electric light socket, to which it is particularly adapted owing to its simplicity, the few parts, and the small space occupied by them. When so used it makes a quick make and a quick break of the electric current, without arcing, upon the rotation of the driving member in either direction.

Among other advantages, my mechanical movement permits the socket to be formed smaller and stronger for the opening in which the mechanical movement is mounted need not be so large as for other switch mechanism. In illustrating my invention I have, therefore, by way of example, shown it as a switch mechanism in an electric light socket, but it is to be understood, of course, that the mechanical movement is not to be limited to this use.

In the accompanying drawings showing illustrative embodiments of my invention and in which the same reference numerals refer to similar parts in the several figures,—Figure 1 is a longitudinal vertical section through my mechanical movement mounted in an electric light socket, the insulating member of the socket being shown in side elevation; Fig. 2 is a longitudinal vertical section substantially on the line 2—2 of Fig. 1, looking in the direction of the ar-

rows; Fig. 3 is a transverse horizontal section substantially on the line 3—3 of Fig. 1, looking in the direction of the arrows; Fig. 4 is a detail plan view of a punching forming a connecting member or link between the driving member and the intermediate or hill and valley member; Fig. 5 is a plan view of the intermediate or hill and valley member; Fig. 6 is a side elevation of the intermediate or hill and valley member shown in Fig. 5; Fig. 7 is a plan view of the blank from which I preferably form the preferred form of resilient driven member; Fig. 8 is a side elevation of the resilient driven member formed from the blank shown in Fig. 7.

In the illustrative embodiment of my invention shown in the drawing, 1 is an electric light socket formed of two complementary insulating members 2 and 3 having meeting surfaces 4, 4.

The driving member 5 is provided with cranks 6, 6 upon which are mounted links 7, 7, one link being mounted upon each crank. These links are preferably formed out of stamped metal and, as shown in Fig. 4, comprise a hollow head 8 having a slot 9 for the reception of the cranks 6 or 7, as the case may be, and are further provided with legs 40, 40 having bent in portions 10, 10, Fig. 4. Upon the legs 40 I mount my intermediate or movable hill and valley member 11 which is preferably formed out of a single stamping, its ends being cut at 12, 12 to form the kickers or accelerators 13, 13, the valleys 14, 14 and the arms 15, 15. By way of example I have shown the kickers or accelerators bent up in one direction, and the arms 15 in the opposite direction, Fig. 6. These arms 15, 15 coöperate with the bent in portions 10 of the links 7 leaving the bent up portions, kickers or accelerators 13 free to coöperate with the end 12 of the resilient driven member 16.

My preferred form of resilient driven member is formed from a stamping. A blank 17, Fig. 7, is stamped from sheet metal and provided with strengthening ribs 18, 18 which are preferably rolled, stamped or otherwise formed. I also preferably provide the blank with offsets 19, 19, one end 20 of the blank being preferably slotted by the slot 21, Fig. 7. When this blank 17 is

bent back upon itself, the resilient driven member 16 is formed, one end being further preferably bent back upon itself to make an engaging arm 22, Figs. 1 and 8, which is adapted to be received in the valleys 14, 14 in the intermediate or movable hill and valley member 11, and to coöperate with the ledge 23 and with the boot, kicker or accelerator 13 in a manner to be hereinafter described.

10 The two coöoperating insulating members 2, 3 are provided with guide grooves 24, 24 within which slide the links 7, 7. By rotating the driving member 5 in either direction, the cranks 6, 6 will reciprocate the links 7, within their grooves 24, carrying with them the intermediate or movable hill and valley member 11. If the driving member 5 is rotated in either direction from the position shown in Fig. 1, the elevated link 7 will cause the end of the plate 11 with which it coöperates, to move down and cause the two ends of the resilient driven member 16 to approach each other until such time as the 25 accelerator or kicker 13 will crowd or force the end 22 out of the valley 14 and over the ledge 23 of the member 11 when the spring or resilient driven member 16 will instantly snap over with a quick and positive snap 30 from the position shown in Fig. 1 to the left until the entire driven resilient member 16 has been moved to the left and its end 22 has been received in the other valley 14 of the intermediate member 11. This movement is 35 instantaneous once the end 22 is released from the particular valley 14 with which it happens to be in engagement. The end of the member 11 which is now shown depressed will then be elevated. By then rotating the driving member 5, in either direction, the resilient driven member 16 will be caused to snap back into the position shown in Fig. 1. I have shown this mechanical movement as a switch mechanism 40 in an electric light socket in which the screw shell 26 has a contact 27, Figs. 1 and 2, which extends within the opening 28 between the insulating members 2 and 3 and spaced from the contact 29 carried by the binding post 45 30. This space is bridged by the resilient driven member 16 when the current is to be passed through the consuming device. The electric current will be made or broken with a quick and positive snap, without arcing, 50 so that both a quick make and a quick break will be made upon the rotation of the driving member 5 in either direction. The screw shell 26 is cut away at 31 so that the center contact 32, which is preferably an arm of the 55 binding plate 33, may be inserted. This binding plate 33 is secured to the insulating member 2 by means of the screw 34. The binding screw 35 is carried by the binding plate 36.

60 55 The binding post 37, carrying the binding

screw 38, is secured to the insulating member 3 by means of the locking screw 39 which serves at the same time to secure the two insulating members 2 and 3 together.

It is, of course, to be understood that while 70 I preferably use one kicker or accelerator with each groove or valley, I may in all forms of my invention omit such accelerators, or use only one.

Having thus described this invention in 75 connection with an illustrative embodiment thereof to the details of which I do not desire to be limited, what is claimed as new and what it is desired to secure by Letters Patent is set forth in the appended claims. 80

1. A mechanical movement comprising a rotary driving member, actuating members upon the driving member, two links, one mounted on each of the actuating members and an intermediate member carried by the 85 links and provided with grooves or valleys in its ends, and a reciprocating resilient driven member having a surface to coöperate with the intermediate hill and valley member. 90

2. A mechanical movement comprising a rotary driving member, actuating members upon the driving member, two links, one mounted on each of the actuating members and an intermediate member provided with 95 grooves or valleys and with one or more accelerators or kickers, and a reciprocating resilient driven member having a surface to coöperate with the intermediate hill and valley member. 100

3. A mechanical movement comprising two reciprocating driving members, an intermediate member connected to the reciprocating members and provided with grooves or valleys at its ends, a reciprocating resilient driven member having a surface to coöperate with the groove or valley in the pivoted intermediate member. 105

4. A mechanical movement comprising a rotary driving member, actuating members 110 upon the driving member, two links, one mounted on each of the actuating members and an intermediate member carried by the links and provided with grooves or valleys in its ends and with retarding means, and 115 a reciprocating resilient driven member having a surface to coöperate with the intermediate hill and valley member.

5. A mechanical movement comprising a rotary driving member, actuating members 120 upon the driving member, two links, one mounted on each of the actuating members and an intermediate member provided with grooves or valleys and with one or more accelerators or kickers and with retarding 125 means, and a reciprocating resilient driven member having a surface to coöperate with the intermediate hill and valley member.

6. A mechanical movement comprising a rotary driving member, actuating members 130

- upon the driving member, two links, one mounted on each of the actuating members and an intermediate member provided with grooves or valleys and with one or more accelerators or kickers and with one or two ledges, and a reciprocating resilient driven member having a surface to coöperate with the intermediate hill and valley member and with the ledges carried by the pivoted intermediate member.
10. An article of manufacture for a mechanical movement comprising an intermediate or hill and valley member formed from sheet metal and having portions of its ends bent in opposite directions to form kickers or accelerators and arms.
15. An article of manufacture for a mechanical movement comprising an intermediate or hill and valley member formed from sheet metal and having depressions or valleys and portions of its ends bent in opposite directions to form kickers or accelerators and arms.
20. An article of manufacture for a mechanical movement comprising an intermediate or hill and valley member formed from sheet metal, its ends being provided with cuts forming prongs some of which are bent in one direction to form shelves, valleys and accelerators and other of the prongs are bent in the opposite direction to form engaging arms.
25. An article of manufacture for a mechanical movement comprising, a link stamped from sheet metal having a slotted head, and depending legs.
30. An article of manufacture for a mechanical movement comprising a link stamped from sheet metal having a slotted head, and depending legs, the depending legs being provided with bent in portions to form engaging surfaces.
35. An article of manufacture for a mechanical movement comprising a link stamped from sheet metal having a slotted head, and depending legs, the depending legs being provided with bent in portions to form engaging surfaces.
40. An article of manufacture for a mechanical movement comprising a link stamped from sheet metal having a slotted head, and depending legs, the depending legs being provided with bent in portions to form engaging surfaces.

TONJES AUGUST CARL BOTH.
